PRINTING MEANS

George W. Darenberg, Freeport, N. Y.

Application November 23, 1942, Serial No. 466,583

8 Claims.

(Cl. 101—122)

This invention relates to printing, and in particular to the ornamentation of a single piece of fabric in panel form and mechanical means for carrying out the printing in a press.

In the production of ornamented window curtains heretofore, it has been the practice to pass the web of fabric through the press and print a design thereon throughout the entire length of the piece from which the curtains are cut. This was found objectionable because the printed design appeared in the hems and folded bindings of the curtains and presented an unsightly appearance. Also when the curtain material was cut for length, the cutting usually mutilated the printed design. The remedy for this objection was to produce a single panel curtain with the side edges and upper and lower edges already hemmed and then to print this panel or single curtain by a hand process that contemplated the use of the silk screen and the careful and frequent handling of the curtain. This process made the cost of the curtains high and as the design had to be placed at exactly the right location in the panel, within, but not touching the hems of the curtain, the printing could not be done by the use of the printing press.

It is the particular object of my invention to provide means including a press for printing on a single panel curtain within the hemmed borders thereof so that the design begins and ends at the proper place on the curtain which is finished except for printing before it is passed through the press to be printed upon through a stencil. A further object of the invention is to provide means for making the feeding of each individual curtain into the press practical and at a minimum of time and also to provide means whereby the stencil may be adjusted to print designs of varying lengths on curtains of various lengths without altering the press or removing the stencil therefrom.

A still further object of the invention is to print, on a single finished curtain through a press mounted stencil, so that the curtains can be fed to the press one after another in quick succession and can be removed from the press automatically. They may be allowed to dry with the design plain, or decorated with flock, tinsel or beads and the like. This process can also be applied to bed-spreads, table cloths, draperies etc.

With these and other objects in view, the invention comprises certain constructions herein-after described and then particularly pointed out in the claims and a preferred embodiment of my

invention is illustrated in the accompanying drawing, in which:

Figure 1 is a view in side elevation, partly in section, of a printing press employing a stencil and inking means through which a completed curtain is passed for printing impression,

Figure 2 is a fragmentary view in perspective showing the means for securing the leading edge of a curtain in place so that it is properly associated with the stencil in its passage through the press,

Figure 3 is an enlarged diagrammatic view showing how the curtain is fed into the press,

Figure 4 is a plan view of a single panel curtain which has been completed and is ready for printing, the lead or gripper strip being shown in place in the bottom hem of the curtain,

Figure 5 is an enlarged section taken on the line 5—5 of Figure 4 showing the lead strip in the hem of the curtain, and

Figure 6 is a plan view of an opened stencil showing how the length of the design may be controlled.

Referring to the drawing in detail, 10 indicates the frame of a printing press of well known construction in which is mounted the impression cylinder 11 for rotation at the same speed as the travel of a perforated stencil web 12 through which designs and the like are printed, in this instance, on a single panel curtain 13 passed between the cylinder 11 and the stencil 12. The method of keeping the cylinder 11 free from printing ink is illustrated in my copending application, Serial No. 393,158. Printing ink or color 14 is contained in an ink reservoir 15 positioned inside the stencil 12 to feed through the openings of the stencil that form the design. The reservoir comprises the usual walls 16, one of which constitutes a doctor blade 17 the pressure of whose edge against the stencil is adjusted by the tension device 18. The slack in the stencil is taken up by a tension device 19.

The frame also supports rollers 20 about which operate the conveyor web 21 positioned beneath the stencil 12 and in position to receive the printed curtain and lead the same from the press, the curtain being indicated by the letter C. Simultaneous operation of the cylinder 11 and stencil 12 is provided by the gears 23, 24 and 25, 50 the latter of which is belt operated as at 26 from a pulley 27. The belt 26 is not normally tight enough to operate pulley 28 to which the power is transferred from pulley 27 to operate the press, so that the press can be operated in a cycle by 55 the operator that feeds the curtains thereto. For

this purpose, I provide a belt tension member 30 depicted as a roller mounted in the end of a foot-lever 31 having a foot pedal 32 in position for easy operation by the press operator at the feed in end of the press. When the lever 31 is depressed to the outline position in Figure 1, the press operates, and stops as soon as the lever is raised by the spring 33. The operation of belt 26 is through the medium of the motor 34 and speed reduction mechanism 35, drive belt 36 and pulley 39 associated with the pulley 21. Operation of the conveyor web 21 is through the belt 40 travelling about cylinder pulley 41, variable speed pulley 42 and tension idler 43.

The design to be printed on the curtain is cut as at 45 in the stencil which passes over the rollers 46, 47 and 48, the latter of which is attached to the gear 23. As the design must be printed at the same place on each curtain and properly within the hemmed edges thereof, the curtain must be fed through the press in proper relation to the stencil and to this end I have provided a gripper strip 50 which may be made of fiber, paper or other suitable material having an attaching portion 51 which is glued or otherwise secured to the stencil 12 to allow the free edge 52 thereof to receive between it and the surface of the stencil, the leading or lower edge of the curtain as shown diagrammatically in Figure 3. The free edge portion of the strip may be solid or slotted as at 53. The slots provide flexibility, break suction or vacuum and allow drop away of the curtain from the stencil very quickly when the stencil clears cylinder 11.

In order to feed the curtain, I have made use of a lead strip of stiff paper or other material, which I pass through the bottom hem of the curtain. The latter is printed from bottom to top. The lead strip 54 extends beyond the curtain at both sides thereof as at 55 to provide hand holds so that the operator can bring the edge of the curtain against the juncture formed by the meeting of the free edge 52 of the gripper strip and the stencil 12. Then foot operation of the pedal 32 will cause operation of the press and the leading edge of the curtain containing the lead strip 54 will be gripped between the stencil and the cylinder 11 and will pass between these two. After the stencil leaves the cylinder, the flexible gripper strip opens or drops to let the lead strip 54 fall down on to the conveyor web 21. The speed of travel of the web 21 may be faster than the travel of the stencil so that the curtain is drawn away from the stencil quickly. After the curtain leaves the conveyor it may be flocked or packed for shipment. The use of the lead strip makes it possible to print the curtain which is of fragile material, in a printing press and in combination with the gripper strip which initiates travel of the curtain through the press is an important part of my invention. The lead strip 54 is heavy enough to drop the leading edge of the printed curtain when the gripper strip opens.

My invention also contemplates the adjustment of the press to accommodate curtains of varying lengths and to do this without removing the stencil, I make use of blocking strips 55 of paper or like material to cover the perforated design in the stencil 12 in accordance with the length of curtain upon which a design is to be printed. The curtains are finished usually in 90, 87, 81, 78 and 72 inch sizes and the design must be shortened to fit the particular size of curtain. The unblocked stencil will accommodate a 90 inch curtain and the blocking strip 55 shown in full lines in Figure

6 will shorten the stencil to produce a design suitable for an 87 inch curtain. The outline indications of other blocking strips or sheets 55 show how the stencil design may be blocked out or covered to give the length of design necessary in accordance with the length of curtain being printed. The area of design on the stencil is represented in outline and designated as at D in Figure 6.

10 My invention is not to be restricted to the precise details of construction shown since various changes and modifications may be made therein without departing from the scope of the invention or sacrificing the advantages derived from its use.

15 What I claim is:

1. In a printing press, in combination, an impression cylinder, a travelling endless stencil web through which is printed a design or the like on a fabric passed between the stencil and said impression cylinder, and a gripping strip on said stencil extending substantially the width of said stencil and presenting an attaching portion and a relatively hinged free portion, the latter being arranged for frictionally holding the leading edge 20 of the fabric between the stencil and the strip as it passes between the stencil and said impression cylinder, and for automatically freeing the leading edge of the fabric by gravity as the stencil leaves the cylinder.

2. In a printing press, in combination, an impression cylinder, a travelling endless stencil web through which is printed a design or the like on fabric passed between said stencil and impression cylinder, said stencil being perforated in a design

35 area and design area covering means for adjusting the length of the design printed on said fabric in accordance with the length of said fabric, and a gripping strip on said stencil web extending substantially the width of the web and presenting an attaching portion and a relatively hinged free portion, the latter being arranged to frictionally hold the leading edge of the fabric between the stencil and the strip as the fabric passes between the stencil and the impression cylinder, said strip automatically freeing the leading edge of the fabric by gravity as the stencil leaves the cylinder.

4. In a printing press, in combination an impression cylinder, a travelling endless stencil web having a perforate area presenting a design 50 through which a print is made on fabric passed between said stencil and impression cylinder, and blocking strips arranged to cover a portion completely of one end of said perforate area to adjust the length of design to the length of fabric being 55 printed upon, and a gripping strip on said stencil web extending substantially the width of the web and presenting an attaching portion and a relatively hinged free portion, the latter being arranged to frictionally hold the leading edge of the fabric between the stencil and the strip as the fabric passes between the stencil and the impression cylinder, said strip automatically freeing the leading edge of the fabric by gravity as the stencil leaves the cylinder.

60 4. In a printing press, in combination, an impression cylinder, a travelling endless stencil web through which a print is made on a piece of fabric passed between said stencil and said impression cylinder, a reinforced leading edge on said fabric 65 and a gripping means on the stencil operable by contact of the cylinder and stencil and coacting with the leading edge of the fabric for feeding the fabric through the press in correct relation with said stencil, and for automatically releasing the fabric when the stencil leaves the cylinder.

5. In a printing press, in combination, an impression cylinder, a travelling endless stencil web through which a print is made on a piece of fabric passing between the stencil and the impression cylinder, a flat flexible removable lead strip in the piece of fabric for reinforcing the edge thereof, a gripping strip on the stencil operable on contact of the cylinder and stencil for engaging said lead strip to feed the fabric through the press and means for blocking out a portion of the design on the stencil lengthwise of the stencil with respect to said gripping means and in accordance with the length of the piece of fabric being printed upon.
6. In a printing press, in combination, an impression cylinder, a travelling endless stencil web through which is printed a design or the like on an unsupported flimsy fabric passed between said stencil and the impression cylinder, a gripping strip on the stencil having a portion attached to the stencil and a portion free therefrom, but foldable against said stencil when the latter engages said impression cylinder, a lead strip in the fabric arranged to be positioned on the gripping strip to be held thereby when the latter is folded, 25 and said lead strip dropping the leading edge of the fabric out of the gripping strip after the latter has passed the impression cylinder.
7. In a printing press, in combination, an impression cylinder, a travelling endless stencil web, 5 a gripping strip on the stencil, a lead strip in one end of a flimsy fabric piece to be printed upon for engagement with said gripping strip when the latter grips the lead strip upon contact of the cylinder and stencil, design area adjusting means for said stencil and a conveyor for leading the printed fabric from the press.
8. In a printing press, in combination, an impression cylinder, a travelling endless stencil web through which is printed a design or the like on a piece of flimsy unsupported fabric passed between the cylinder and the stencil, means for controlling the operation of the press for a single printing cycle, a gripping strip on the stencil, a lead strip on the fabric piece to be printed upon, said lead strip being engaged and held by the gripping strip during contact of the cylinder and stencil to draw the fabric through the press, and the gripper strip automatically releasing the lead strip to discharge the fabric from the press.

GEORGE W. DARENBERG.
